(57) **CLAIM**

The ornamental design for a container for dosimeter, as shown and described.

DESCRIPTION

FIG. 1 is a perspective view of a container for dosimeter showing our new design;

FIG. 2 is a front elevational view thereof, the rear elevational view being identical thereto;

FIG. 3 is a top plan view thereof, the bottom plan view being identical thereof;

FIG. 4 is a right side view thereof, the left side being identical thereto;

FIG. 5 is a cross-sectional view taken along line 5-5 of FIG. 2;

FIG. 6 is a perspective view of a lid portion of the container for dosimeter;

FIG. 7 is a front elevational view of the lid portion, the rear elevational view being identical thereto;

FIG. 8 is top plan view of the lid portion, the bottom plan view being identical thereto;

FIG. 9 is a right side view of the lid portion;

FIG. 10 is left side view of the lid portion;

FIG. 11 is a perspective view of a main body member of the container for dosimeter;

FIG. 12 is a front elevational view of the main body member, the rear elevational view being identical thereto;

FIG. 13 is top plan view of the main body member, the bottom plan view being identical thereto;

FIG. 14 is a right side view of the main body member;

FIG. 15 is left side view of the main body member; and,

FIG. 16 is a perspective view of the container for dosimeter in use.

The broken line showing is for the purpose of illustrating environmental structure which forms no part of the claimed design.

1 Claim, 8 Drawing Sheets
